UNITED STATES PATENT OFFICE.

JOSEPH LUNT, OF STOKE-UPON-TRENT, AND JOHN WILLIAM HARTLEY, OF STONE,
ENGLAND.

CIRCULAR KILN OR OVEN.

1,028,043.

Specification of Letters Patent.

Patented May 28, 1912.

Application filed March 6, 1911. Serial No. 612,571.

To all whom it may concern:

Be it known that we, JOSEPH LUNT and JOHN WILLIAM HARTLEY, subjects of the King of England, residing at Stoke-upon-Trent and Stone, respectively, in the county of Stafford, England, have invented certain new and useful Improvements in Circular Kilns or Ovens; and we do hereby declare the following to be a full, clear, and exact 10 description of the invention, such as will enable others skilled in the art to which it appertains to make and use the same, reference being had to the accompanying drawings, and to letters or figures of reference marked thereon, which form a part of 15 this specification.

This invention relates to kilns or ovens for use in the firing, heating, annealing or drying of pottery, glass enamel goods, cress, sand and other materials, and particularly to circular kilns or ovens wherein the firing zone is usually on one side of the kiln and the opening on the opposite side. In this particular type of kiln, the wares, or other 20 contents, pass through an annular chamber, forming the kiln proper, the contents being carried in metal baskets or the like. The baskets are usually supported either on rollers, or sliding plates which rest on 25 the bottom of the kiln, or on wheeled carriages which travel on a rail track below the kiln bottom, the carriages carrying the baskets around by means of supports passing through an annular slot in the bottom 30 of the kiln. The heat of the kiln in the latter case is retained by fence plates which plow through sand filled grooves or channels which are difficult of access under present conditions and frequently become defective resulting in considerable loss of heat, and as the flues cannot pass beneath the annular chamber, bottom heat cannot easily be 35 secured.

One object of the present invention is to 40 enable the baskets or their carriers to be supported from without the kiln, so that external sand grooves and fence plates may be used, readily accessible and capable of always being maintained in proper order 45 to avoid loss of heat.

Another object is to enable the support for the baskets or their carriers to be taken from a structure or foundation distinct from the brickwork of the kiln, whereby vi-

bration and damage to the structure of the 55 kiln are avoided.

Further objects are to effect economy in the construction and wear and tear of the kiln and in the power required to move the wares or product being heated. 60

The invention consists in providing a circular slot or groove in the roof of the kiln in order that the baskets or the like, or their carriers, may be suspended from without the kiln. 65

The invention also consists in suspending baskets or their carriers by links or the like members passing through the annular or circular slot in the roof of the annular chamber; in carrying the links by suitable traveling means situated outside the kiln; and in fitting said carrying means with fence plates adapted to plow through sand filled grooves or channels in the outer surface of the roof of the chamber. 70

The invention further consists in carrying the links or the like upon a turntable in the form of a trussed frame or other structure pivotally supported on a central pillar or other support distinct from the brick-work of the kiln proper, so as to relieve the latter of the weight of, and consequent vibration of, the baskets or their carriers. 75

The invention still further comprises the provision of one or more tie bands on the 80 bricks forming the sides of the sand grooves, and other details hereinafter referred to.

The accompanying drawings illustrate several forms of kiln according to the present invention. 85

Figures 1 and 2 are cross-sectional elevations through the charging and discharging positions of one form of kiln illustrated by way of example for use in the roasting of 90 ores or sand. Fig. 3, is a detail side elevation illustrating one mode of discharging the buckets. Figs. 4 and 5 are respectively a plan, half in section, and a sectional elevation of another form of the invention, illustrated by way of example for use in the 95 heating, firing or drying of pottery, enamel goods or the like. Fig. 6, being a cross-sectional elevation of the same on a larger scale. Figs. 7 and 8, are respectively a sectional elevation and a part plan illustrating 100 an alternative mode of mounting the trussed frame. 105

In carrying out the invention according to one mode, for example, as applied to a kiln for roasting sand or ores, and as illustrated in Figs. 1 to 3, the annular chamber *a*, of the kiln is provided with an annular or circular slot *b*, in the roof *c*. The buckets *d*, for sand or other material, are pivoted on trunnions *3*, to a frame of bars *o*, carried by suitable suspending members such as 5 hangers or links *e*, which pass through the slot *b*, and are suspended from an iron frame *f*, fitted with wheels *g*, running on rails *h*, mounted on the top of the chamber *a*. The frame *f*, or links *e*, are provided 10 with fence plates *i*, which enter and plow through sand in grooves or channels *k*, so as to prevent loss of heat through the slot *b*. The frame *f*, can be traveled around on the rails in any suitable manner either by hand 15 or power, for instance, a handle *1*, may drive the frame through reduction gearing *m*, the last pinion *m'* of which meshes with an annular rack *m²*. The buckets *d*, may be successively charged with sand or other material through a chute *4*, Fig. 1, and as they 20 reach a discharge chute *5*, Fig. 2, they may be automatically tipped to discharge their contents therethrough. For instance, short levers *6*, on the trunnions of the buckets 25 may engage a fixed pin or stop *7*, Fig. 3, the buckets being so balanced that they return to the horizontal position after discharging. The adjacent buckets overlap each other at their ends.

30 In another mode of carrying out the invention, in the application to a kiln for firing or heating pottery, enamel wares, or the like purposes and as illustrated by Figs. 4 to 6, the baskets or crates *d*, are carried upon an annular frame *o*, preferably constructed in segments, the frame *o*, being suspended by links *e*, slung from a revolving circular upper frame *x*, preferably of trussed formation. The frame *x*, rotates about a central pillar *p*, having a ball or roller bearing 35 *q*, on a brickwork or other foundation which is distinct from the brickwork of the kiln proper or chamber *a*. In this way the chamber *a*, is relieved of the weight of the crates and traveling frame; and the liability 40 to damage or dislocation of the brickwork by the vibration of the traveling wheels is avoided.

45 In applying the invention to a kiln having a central chimney, and as illustrated in Figs. 7 and 8, the trusses of the frame *x*, may be carried upon suitable rings *8, 9* encircling the chimney.

50 In order to steady the frame *x*, a series of 55 rollers *r*, may be arranged in suitable positions, for instance, at the outer ends of the horizontal members of the trusses, the rollers *r*, resting lightly on a metal band or rail *s*, extending around the kiln and also serving 60 as a tie-band.

The roof of the chamber *a*, may be formed of fire-bricks *t*, suitably rabbeted together and are provided with the sand grooves *k*; and an abutment *u'*, may be erected to take the tie-band *s*.

65 In addition to fence plates *i*, fire-clay tiles or iron plates *u*, may be placed over the circular slot *b*, as an additional preventive against loss of heat. The tiles or plates *u*, may be supported loosely within and upon 70 the fence plates, so that they may yield if, during the revolution of the frame *x*, the tiles should press upon the inner walls *v*, of the said grooves. The inner walls *v*, are preferably raised above the outer walls to 75 prevent sand falling through the slot *b*. Shields *12*, may be fitted on the hangers *e*, to divert any sand which may happen to fall in. In order to insure against the 80 groove or slot *b*, being closed, due to expansion of the kiln, a tie-band *10*, is arranged against the one side of the inner sand groove *k*, and a similar band *11*, may also be provided against the outer side of the other groove *k*. It will be understood, however, 85 that the tie-band *10*, is more important than the band *11*, as it will resist outward movement of the kiln top under heat.

90 The trussed frame *x*, may be revolved by hand; for instance, the horizontal members *95* may be prolonged to form handles *13*, the arrangement greatly reducing the power required compared with that first described with reference to Figs. 1 and 2.

95 The baskets or crates *d*, are preferably 100 placed upon the lower frame *o*, by a forked lever through a side door *14*, Fig. 5, opposite to the heated zone, the frame being recessed to allow clearance for the arms of the lever to pass beneath the baskets.

105 In Figs. 4 and 6, the furnace is indicated at 15, the gases from which pass through flues *16*, under the bottom of the kiln or chamber *a*, up three flues *17*, on each side, down the next three flues *18*, under the bottom again, up the succeeding three flues *19*, along the side and then down the last three flues *20*, and thence to the chimney *21*. It will 110 be understood, however, that the arrangement of heating may be varied to suit the character of the goods or materials to be treated, and that the invention is not confined to any particular arrangement of crate or carrier as such a detail may be varied to suit the character of the goods to be treated, 115 for instance the crates may be arranged in tiers.

120 We claim:—

1. In combination with the side walls and floor of a circular kiln, overhanging 125 brickwork roof parts, said parts being spaced so as to leave between them an annular slot, and means for retaining said slot in circular form, an arm supported transversely to said slot, a suspending rod sup- 130

ported from said arm, and passing through said slot and supporting cages carried by said suspending rods.

2. In combination with the side walls and floor of a circular kiln, overhanging brick-work roof parts, said parts being spaced so as to leave between them an annular slot, means for retaining said slot in circular form, an arm supported transversely to said slot, a suspending rod supported from said arm, and passing through said slot, supporting cages carried by said suspending rods and a central pivot from which said arms radiate.

15 3. In combination with the side walls and floor of a circular kiln, overhanging brick-work roof parts, said parts being spaced so as to leave between them an annular slot, means for retaining said slot in circular form comprising a metal binding ring located on said roof radially within said slot, transverse bars supported above said annular slot, suspending rods carried by said transverse bars and passing through said slot and supporting cages carried by said suspending rods.

4. In combination with the side walls and floor of a circular kiln, overhanging brickwork roof parts, said parts being spaced so as to leave between them an annular slot, means for retaining said slot in circular form comprising a metal binding ring located on said roof radially within said slot, a central pivot, arms radiating from said pivot and extending above said annular slot, suspending rods supported from said arms and passing through said slot, supporting cages within said kiln and carried by said suspending rods, bearer wheels on the end of said radiating arms and a bearer rail on the roof of the kiln and near the outer wall of the same, on which rail said bearer wheels rest.

30 5. In combination with the side walls and floor of a circular kiln, overhanging brick-work roof parts, said parts being spaced so

as to leave between them an annular slot, means for retaining said slot in circular form comprising a metal binding ring 45 located on said roof radially within said slot, a central pivot, arms radiating from said pivot and extending above said annular slot, suspending rods supported from said arms and passing through said slot, supporting 50 cages within said kiln and carried by said suspending rods, means for preventing egress of hot gases through said slot comprising sand channels in said overhanging roof parts on either side of said annular slot, 55 tile plates carried by said suspending rods and movable over said slots and fence plates projecting from the ends of said tile plates and plowing in said sand channels.

6. In combination with the side walls and floor of a circular kiln, overhanging brick-work roof parts, said parts being spaced so as to leave between them an annular slot, means for retaining said slot in circular form comprising a metal binding ring 65 located on said roof radially within said slot, a central pivot, arms radiating from said pivot and extending above said annular slot, suspending rods supported from said arms and passing through said slot, 70 supporting cages within said kiln and carried by said suspending rods, bearer wheels on the end of said radiating arms and a bearer rail on the roof of the kiln and near the outer wall of the same, on which rail 75 said bearer wheels rest.

In testimony whereof we have signed our names to this specification in the presence of two subscribing witnesses.
